UNITED STATES PATENT OFFICE.

WILLIAM T. ANGELL, OF CHICAGO, ILLINOIS.

PUMP-VALVE.

1,159,347.

Specification of Letters Patent

Patented Nov. 9, 1915.

Application filed July 25, 1914. Serial No. 853,020.

To all whom it may concern:

Be it known that I, WILLIAM T. ANGELL, a citizen of the United States of America, and a resident of Chicago, county of Cook, State of Illinois, have invented certain new and useful Improvements in Pump-Valves, of which the following is a specification.

My invention relates to pump valves and has for its object improvements in the valve itself and in the parts immediately associated therewith.

In the accompanying drawings Figure 1 is an elevation being mainly in section on line 1—1 of Fig. 2; Fig. 2 is a plan, the upper parts being in section on line 2—2 of Fig. 1; and Fig. 3 is a side elevation being partly in section on the broken line 3—3 of Fig. 1.

The ring 1 is provided with threads 2 adapted to be screwed into the valve deck of a pump. On the seat 3 is a packing ring 4 held in an annular groove in the valve body 5. The lower face of the valve body is in the form of an inverted cone 6 having a curved slope 7, and the inner face of the ring 1 is in the form of an inwardly convex curve 8 connecting the inner edge of the seat 3 with the bottom threaded portion of the ring 1. These curves 7 and 8 are designed to give an easy and smooth flow of water upward through the ring 1 when the valve rises from its seat. It will be observed that the water opening through the ring is not obstructed by any bridges as in ordinary pump valves of this type, and it is one of the objects of the present construction to avoid the necessity of such obstructions.

On the top of the ring 1 are posts 9 and 10 which rise above the top of the valve body 5 and serve as lower guides for the valve as it rises from its seat. These posts are made substantial enough to serve as means for screwing the ring 1 to its place in the valve deck by placing a bar across the ring and using it as a lever engaging the posts to turn the ring.

Extending over the center of the valve, and engaging the outer faces of the posts 9, is a spring 11 of bronze or other non-rusting material. The legs of this spring bridge preferably rest upon the smooth upper face of the ring 1 and are provided with holes for engaging the projecting pins 12 in the posts 9. It will be obvious that the bearing of the legs of the spring 11 upon the ring 1

and the engagement of the spring with the pins 12 serve as means for holding the spring bridge in its proper position over the center of the valve. Also that by springing one of the legs of the bridge outward so as to free it from its pin 12, the said bridge may be easily removed.

On the center of the valve body 5, and preferably integral therewith, is a stem 13 which passes through a hole in the center of the bridge 11 and serves as an upper guide for the valve in its movements. The hole in the bridge is preferably formed by forcing part of the metal of the bridge inward to form a ring 14 surrounding the stem 13, and the upper part of the stem 13 is preferably made smaller than the lower part so as to form a shoulder 15 to limit the upward movement of the valve.

Surrounding the stem 13, and between the bridge 11 and the valve body 5, is a helical spring 16 which serves to normally hold the valve to its seat. For valves working under light water pressure, the upper face of the valve body may be recessed as shown at 17 to give a greater length to spring 16, but for heavy water pressures it is preferable to omit the recess for purposes of strength and stiffness in the valve body.

Valves of this type are usually placed in positions having restricted overhead space. The spring bridge construction enables me to obtain ample lift to the valve with very little vertical height over all, and at the same time furnishes an easy means for removing the valve in this restricted space. By making a valve seat without bridges across the port to furnish a valve guide I am enabled to provide a fuller and freer port opening for the same size of aperture, and at the same time to use only one packing ring 4.

I am aware that valve ports without bridges are common in many kinds of valves, but I am not aware that they have heretofore been used in the type of valve herein described. An illustration of the type of valve to which I refer may be found in patent to Woodford, No. 794,209, dated July 11, 1905.

What I claim is:—

1. A valve seat providing a port and having valve guiding posts outside of and above the seat, a valve within said guides, said valve being provided with an upwardly projecting stem, and a removable spring bridge

secured to two of said posts and serving to guide the upper end of the valve stem.

2. A valve seat providing an unobstructed port and having short valve guides consisting of posts projecting upward about said seat, a valve within the guides and resting upon the seat, said valve having the central part of its lower face in the form of a curved cone projecting into the center of the port 10 and said cone being adapted to pass laterally between the posts when the valve is raised to a position with its face level with the tops of said posts, and a removable guide for said valve above the tops of said 15 posts.

3. The combination with a ring providing an unobstructed port, a valve seat and posts serving as means for screwing the ring into and removing it from position in a pump, of 20 a valve resting upon the seat and guided by the posts, said valve being provided with an upwardly projecting stem, and a removable

bridge secured to two of said posts and serving to guide the upper end of the valve stem.

4. The combination with a ring providing an unobstructed port, a valve seat and short valve guiding posts located about said seat, of a valve resting upon the seat and guided by said posts, said valve being provided with an upwardly projecting stem and a downwardly projecting cone adapted to pass between adjacent posts when the valve face is raised above the tops of said posts, and removable bridge for guiding the upper end 35 of said stem, said bridge and stem being arranged to prevent the valve from rising above the tops of the guiding posts.

Signed at Chicago, Illinois this 23rd day of July, 1910.

WILLIAM T. ANGELL.
